Fred Prior, Dallas, Tex.

Application October 20, 1944, Serial No. 115,893

Term of patent 14 years

(Cl. D14—6)

To all whom it may concern:

Be it known that I, Fred Prior, a citizen of the United States, residing at Dallas, in the county of Dallas and State of Texas, have invented a new, original, and ornamental Design for a Fuel Tank Mounted Toolbox for a Truck or Similar Article, of which the following is a specification, reference being had to the accompanying drawing, forming part thereof.

Figure 1 is a perspective view of a fuel tank mounted toolbox for a truck or similar article showing my new design.

Figure 2 is a side elevational view, and
Figure 3 is an end elevational view.

I claim:

The ornamental design for a fuel tank mounted toolbox for a truck or similar article, as shown.

FRED PRIOR.
